ATTORNEY:

UNITED STATES PATENT OFFICE.

FRANK GWILLIAM, OF NORTON, MASSACHUSETTS.

EXPANSIBLE CUFF BUTTON.

Application filed February 13, 1924. Serial No. 692,613.

To all whom it may concern:

Be it known that I, FRANK GWILLIAM, a citizen of the United States, residing at Norton, county of Bristol, State of Massachusetts, have invented a certain new and useful Improvement in Expansible Cuff Buttons, of which the following is a specification, reference being had therein to the accompanying drawings.

10 The invention relates to a new and useful improvement in cuff links. In order to widen the hand passage through the cuff for putting the shirt on and off and to allow the cuffs to be rolled back without removing 15 the links, separable links have come much into vogue. One objection to many of the separable links is that after some time the connection between the two members becomes so worn or the spring catch becomes 20 so weakened that the two members are apt to become separated when they are intended to remain connected. Another objection is that when the two members are unconnected they are liable to be lost. The 25 object of the present invention is to provide a button or link having two heads and an expansible connecting shank or post which permanently connects the two heads but which is expansible to allow the two 30 heads to be more widely spread apart from each other and thereby permit the cuff to be opened more widely for the passage of the hand in putting the shirt on and off.

The invention will be fully understood 35 from the following description when taken in connection with the accompanying drawings, and the novel features thereof will be pointed out and clearly defined in the claims at the close of this specification.

40 In the drawings:

Fig. 1 is a side elevation of a button embodying the invention showing the parts in normal position with its shank in its contracted form.

45 Fig. 2 is a side elevation showing the button shank expanded.

Fig. 3 is a longitudinal section of the unexpanded button on line 3—3, Fig. 1.

50 Fig. 4 is a longitudinal section of the expanded button on line 4—4, Fig. 2.

Referring now to the drawings: There are shown at A and B the two heads of the button. The head A has a tubular post member 1 secured thereto by soldering or 55 otherwise as will be well understood. This

tubular member 1 is of the length of the normal distance between the two heads A and B when the link is unexpanded, as shown in Figs. 1 and 3.

The head B has a tubular post 2 secured thereto, said post being preferably equal in length to the tubular member 1 although not necessarily as long. It is of smaller diameter than the member 1 so that the smaller member 2 may be telescoped into the larger member. For the purpose of the invention only two telescopic members are required but three give still greater expansibility. An intermediate tubular member 3 is preferably provided which in size is also intermediate the two members 1 and 2 so that the member 2 may telescope into the member 3 and the member 3 may telescope into the member 1.

In order to prevent the tubular members from becoming separated from each other after they are assembled and also to form seats for the springs, as will be hereinafter described, the tubular member 3 is formed with an annular lip or flange 4 which extends radially outward from the end which slides in the member 1 and the member 2 is formed with an outer annular lip or flange 5 at the end which slides in the member 3, the two flanges 4 and 5 having a sliding fit 85 respectively in the tubular members 1 and 3. The parts will be assembled thus far before the outer ends of the members 1 and 3 respectively are crimped in. While the tubular members are in assembled relation and 90 before the outer ends are crimped, annular spiral springs 6 and 7 are inserted respectively into the space between the members 1 and 3 and between the members 3 and 4, the spring 6 being seated at one end on the 95 lip 4 and the spring 7 being seated on the lip 5. The springs are normally in expanded form and extend the full length of the tubular members, as shown in Fig. 3.

The outer end of the tubular member 1 is 100 then crimped in to form an annular lip 8 which has a sliding fit on the outer periphery of the tubular member 3 and the member 3 is crimped at one end to form an annular lip 9 which has a sliding fit on the outer 105 periphery of the tubular member 2. The lip 8 forms a seat for the outer end of the spring 6 and the lip 9 forms a seat for the outer end of the spring 7.

The springs 6 and 7 are normally in ex- 110

panded form and retain the tubular members in closed position all telescoped together, as shown in Figs. 1 and 3.

When it is desired to expand the link so as to move the two heads A and B farther away from each other, the said heads may be readily moved apart by grasping the two heads and pulling them in opposite directions. This will open out the telescoped members, thereby contracting the springs, as shown in Fig. 4, and if this is done while the two heads are engaged with the two buttonholes in opposite sides of a cuff, it will open out the cuff. When the spreading pressure on the two heads A and B is released, the springs will expand and close the tubular members of the button into each other again.

The springs should be of sufficient power to normally retain the tubular members in closed telescopic relation and yet should yield readily enough so that by simply thrusting the hand through the cuff opening, as in the act of putting a shirt on and off, the lateral pressure of the hand if it fits closely in the cuff as it is drawn through will be sufficient to spread open the link without necessitating the actual manipulation of the two heads of the button by the fingers.

It is obvious that the number of telescopic members may be more or less as desired. There must be at least two. Three are shown in the drawings as already described and there may be more than three if desired. The invention consists primarily in the use of a plurality of telescopic members to permit expansion and means for preventing accidental complete separation of the telescopic members from each other.

What I claim is:

- 40 1. A cuff link having two button members, tubular members permanently connected respectively with said button members, one of said tubular members being of smaller outside diameter than the inside diameter of the other of said tubular members, the smaller tubular member having at its inner end a lip extending radially outward and the larger tubular member having at its inner end a lip extending radially inward, a tubular member of intermediate size having telescopic connection with both of the other tubular members and having at one end an inwardly turned lip and at its other end an outwardly turned lip to cooperate respectively with the lips at the ends of the other tubular members, and coil springs in the

spaces between the adjacent walls of the telescoping members which normally maintain the telescoping members closed, the tubular member which is of the largest diameter being of sufficient length so that when the parts are in normal closed position, the other tubular members will both be entirely enclosed within said larger member.

2. A cuff link having two button members, tubular members permanently connected respectively with said button members, one of said tubular members being of smaller outside diameter than the inside diameter of the other of said tubular members, the smaller tubular member having at its inner end a lip extending radially outward and the larger tubular member having at its inner end a lip extending radially inward, a tubular member of intermediate size having telescopic connection with both of the other tubular members and having at one end an inwardly turned lip and at its other end an outwardly turned lip to cooperate respectively with the lips at the ends of the other tubular members, and coil springs in the spaces between the adjacent walls of the telescoping members which normally maintain the telescoping members closed, the tubular member which is of the largest diameter being of sufficient length so that when the parts are in normal closed position, the other tubular members will both be entirely enclosed within said larger member, the springs being compressed and put under tension by spreading the button members further apart to expand the link.

3. An expansible cuff link button having two button members and a connecting link comprising two tubular members connected respectively with the two button members and an intermediate tubular member, all of said tubular members having telescopic connection with each other and of such relative sizes that when the link is in its most contracted form, one of said tubular members will enclose the others, compression springs enclosed in annular spaces between the walls of the intermediate tubular member and each of the adjacent tubular members, said springs normally holding the tubular members closed together and being compressed and put under tension when the link is expanded by opening out the telescopic members.

In testimony whereof I affix my signature.
FRANK GWILLIAM.
